DOLL EYES

Filed Jan. 25, 1929

UNITED STATES PATENT OFFICE

SAMUEL MARCUS, OF RIVERDALE, NEW YORK, ASSIGNOR TO MARKON MANUFACTURING CO., INC., OF NEW YORK, N. Y., A CORPORATION OF NEW YORK

DOLL EYES

Application filed January 25, 1929. Serial No. 334,896.

This invention relates to an improvement in doll eyes, and an object thereof is to provide means whereby doll eyes may be adjustably connected with their supporting cross rod.

A further object is to provide means by which to definitely limit the extent of adjustability, so as thereby to prevent unintentional injury to the eye structure.

10 A more detailed object is to provide an eye which is adjustably movable with respect to its supporting cross rod in various directions to wit: longitudinally along the cross rod, rotatably about the cross rod, rotatively about a horizontal axis transverse to the length of the rod and rotatively about a vertical axis transverse to the length of the cross rod, and to provide means for limiting the adjustability of the eye about said 20 last mentioned axis.

A further detailed object is to provide means carried by the eye for directly engaging a cylindrical cross rod to permit adjustment of the eye longitudinally and rotatably 25 of said rod, which means comprises parts formed all from a single integral piece of material adapted to provide a uniformly firm frictional grip upon the cross rod notwithstanding considerable variation in the 30 diameter of the cross rod.

A further object is to provide a metallic eye shell made up to include a main semispherical body and means by which said body may be connected with the cross rod to permit 35 adjustment of said shell longitudinally along the cross rod, rotatably about the cross rod, and rotatively about a vertical axis transverse to the length of the cross rod, also limiting means with respect to the last 40 mentioned feature of adjustability, all from a single piece of sheet metal.

Other objects and aims of the invention, more or less specific than those referred to above, will be in part obvious and in part 45 pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a rear elevational view of a portion of an eye set constructed in accordance with this invention. 55

Fig. 2 is a side elevational view of one of the eyes of said set, the view being taken from the point as indicated by the arrow 60 L in Fig. 1.

Fig. 3 is a transverse sectional view taken substantially upon the plane of line III—III of Fig. 1.

Fig. 4 is an enlarged side elevational view, 65 partly in section, taken upon the plane of line IV—IV of Fig. 1, and

Fig. 5 is a fragmentary sectional view taken upon the plane of line V—V of Fig. 1.

Referring to the drawing for describing in detail the exemplary structure illustrated therein, the reference characters G and H indicate generally the two eyes of the set. These are connected together by a cylindrical cross rod 1 which may be mounted in a doll 70 head in any approved manner as by means of a bracket member 2, and which may carry the usual gravity control device including a weight 3 rigidly connected with the cross rod by a weight arm 4. 75

The eye G, which is of course usually a duplicate of eye H, is made up entirely of a single piece of sheet metal the central portion of which constitutes a back plate as 5 of the eye shell, and marginal portions of which include segmental parts as 6—6 bent forwardly to constitute the main semispherical body as indicated generally by the reference character 7 in Fig. 2. 85

About the outer surface of the body 7 there is fitted a separate shell as 8, usually of celluloid, carrying the iris picture 9 and eyelid color 10 said shell 8 being connected with the main body in any appropriate manner usually by having its rear marginal edge folded around the rear annular edge of the body 7, as indicated at 11 in Fig. 4, said shell 8 being thus connected for rotative adjustment upon the body 7 about an axis which in the finished article is substantially horizontal. 90

and transverse to the length of the cross rod. The frictional engagement of the shell 8 with the main body 7 is sufficient to retain the shell 8 in any position into which it has been adjusted.

5 The back plate 5 is provided with a series of alternately oppositely pressed yokes as 12, 13, 14, 15 and 16 collectively defining a horizontal bearing through which the cylindrical cross rod 1 extends, said yokes having frictional engagement with the cylindrical surface of the cross rod to frictionally hold the plate, and hence the entire eye structure, in any position upon the cross rod to which 10 the eye structure may be moved either longitudinally or rotatively of the cross rod.

It is a particular feature of the present improvement that these yokes which are formed up as integral parts of the back plate 5 shall 20 be so shaped as to have each only two points of contact with the cross rod. The yokes 13 and 15 have contact with the cross rod only at the points indicated 17 and 18 while the yokes 12, 14 and 16 have contact only at the 25 points 19 and 20, as clearly shown in Fig. 4. Each yoke is shaped so that, instead of being of a true semicircular form corresponding with the cylindrical contour of the cross rod, it provides two distinct angularly related 30 leaf-spring elements as 21 and 22 bearing against the cross rod at their mid portions, said mid portions being thereby free to yield to considerable extents for accommodating variations in the diameters of different cross 35 rods. The adjacent ends of the leaf-springs extend away from the cross rod and are connected together as at 23. The outer ends of said leaf-springs also extend away from the cross rod and merge into the back plate 5.

40 It will be understood of course that eyes of the type here concerned are made up in large quantities, as are also the cross rods with their brackets and gravity weight etc., and that the eyes are connected with opposite 45 ends of the cross rod by being forcefully telescoped over said ends and adjusted thereon into the desired positions. The diameters of different cross rods vary to considerable extent. Even the circular contour of different 50 cross rods is not always truly circular. Also the bearings defined by the several yokes in different eyes, although made from the same die, vary to slight extents due to different causes which are well understood in this art. 55 By making the yokes to comprise distinct leaf-spring sections as indicated a substantially uniform degree of frictional engagement between the yokes and cross rods is provided even in the presence of material variation 60 of the kinds referred to.

At opposite sides of the cross rod, that is at points above and below the cross rod, the back plate is shaped to provide reduced arms 24—24 from the outer ends of each of which 65 continues a pair of fingers 25—25 spaced

apart and constituting the only direct connection between the back plate and the body 7. Both the arms and the fingers are bendable and being substantially aligned transversely of the cross rod constitute a connection 70 between the body 7 and the cross rod by which the body is adjustable about a vertical axis transversely of the cross rod.

The fingers 25 are relatively more easily bendable than the arms 24 and, being spaced 75 apart circumferentially of the rear edge of the body, are so located that whereas an adjusting movement of the body rotatively of the vertical axis just mentioned will cause a twisting or torsional strain upon the arms 80 it will cause only a straight bending strain upon the fingers. An adjusting movement of the body in one rotary direction will cause the fingers at one side of the axis of rotation to bend relatively inwardly while the fingers 85 at the opposite side of the axis will bend relatively outwardly. An adjusting movement of the body in the opposite rotary direction will cause a reverse bending of the fingers respectively, the torsional twisting 90 movement of the arms meanwhile always serving to insure movement of the body about a substantially fixed axis.

In order to limit rotary adjustment of the body 7 about the vertical axis defined by 95 the arms 24 the present invention proposes additionally that the back plate 5 may be formed with extensions as 26 at opposite sides of the axis defined by the arms 24 spaced a suitable distance beneath opposing extensions as 27 provided upon the body 7, the space as 28 between the extensions 26 and 27, see Fig. 5, being estimated to cause 100 said extensions to engage together only when the body 7 has been moved to the maximum extent necessary for normal use.

As many changes could be made in this construction without departing from the scope of the invention as defined in the following claims, it is intended that all matter contained in the above description, or shown in the accompanying drawing, shall 110 be interpreted as illustrative only and not in a limiting sense.

Having thus described my invention, what 115 I claim as new and desire to secure by Letters Patent is:—

1. A doll eye set comprising a cross rod, means to rotatably support the cross rod, a pair of eyes, and means by which said eyes are connected with the cross rod, the means by which at least one of said eyes is connected with the cross rod consisting of a back plate formed as a part of the eye and having a plurality of yokes pressed therein projecting in alternate opposite directions to collectively form a bearing within which the cross rod frictionally engages, said yokes each being of resilient material and each being shaped to constitute two leaf-spring sections, 120 125 130

each leaf-spring section having frictional engagement with the cross rod at the mid portion only of the length of the respective section, the opposite end portions of the respective sections projecting tangentially away from the cross rod, the bearing thus defined by said leaf spring sections providing four points of contact with the cross rod spaced substantially equi-distant circumferentially of the cross rod and being normally too small to receive the cross rod but the flexibility of the leaf spring sections enabling forced insertion of the cross rod.

2. A doll eye comprising a hemispherical body, and a back plate at the rear of said body, said back plate having means defining a bearing within which to receive a cross rod for the support of the eye, said back plate being also shaped to define a pair of aligned arms integral therewith projecting at opposite sides of the bearing, each of said arms having a pair of fingers projecting therefrom integral therewith spaced apart and continuing into connection with the body, said arms and said fingers all being independently bendable to collectively define an axis about which the body is adjustable with respect to the back plate.

3. A doll eye comprising a hemispherical body, and a back plate at the rear of said body having means for the attachment of a cross rod thereto, said body and said back plate being formed from a single integral piece of sheet material the back plate being the central portion of said piece of sheet material and the body being formed as bent marginal parts of said piece of sheet material, the portion of the sheet of material constituting the back plate being severed from the portion constituting the body except at two localities disposed respectively at opposite sides of the cross rod attaching means, said sheet material at said mentioned localities being bendable to define an axis of rotary adjustment of the body with respect to the back plate, and the severed edges of the back plate at opposite sides of said axis being spaced in opposed relation from the adjacent severed edges of the body to constitute stops adapted to abut together for limiting relative rotary adjustment of the body and back plate.

In testimony whereof I affix my signature.
SAMUEL MARCUS.
